UNITED STATES PATENT OFFICE.

AURÈLE VERMEULEN, OF LOS ANGELES, CALIFORNIA, ASSIGNOR OF ONE-HALF TO
WILLIAM D. HAMMOND, OF LOS ANGELES, CALIFORNIA.

BUILDING CONSTRUCTION.

Application filed June 13, 1921. Serial No. 477,085.

To all whom it may concern:

Be it known that I, AURÈLE VERMEULEN, a citizen of the United States, residing at Los Angeles, in the county of Los Angeles, and State of California, have invented new and useful Improvements in Building Constructions, of which the following is a specification.

This invention relates to building construction, and particularly to building construction wherein tile is used. It is ordinary practice in building construction where roofing tiles are used to have frame members or rafters and sheathing of wood. The building otherwise may be fireproof, but when the roof is reached combustible material is used. As a consequence when a fire occurs the roof will burn and if tile has been laid upon the rafters of course the tile will fall in upon the building.

An object of this invention is to do away with the ordinary wooden rafters and sheathing to form a roof which is absolutely fireproof; another object is the provision of a roof which uses tile, which provides for a light construction and yet provides a construction which readily resists stresses.

In practicing the invention I provide foraminous metallic members laid upon and fastened to channel iron members, which channel iron members take the place of the usual rafters in roof construction. Over the foraminous members I lay the tile members and preferably fasten the tile members at one point to said foraminous members. It is known in mechanics that a network of steel laths forms a rigid construction and one that is not likely to buckle, but which will resist stress in all directions. If this network is reinforced by longitudinal or lateral members, or both, we have a construction that is at once rigid and which will sustain an immense amount of weight, and at the same time be light in construction. Tile is very heavy, varying from 750 to 1500 pounds or more per square. It would therefore appear that even for light tile the rafters or frame work must be very strong and therefore the advantage gained by a construction like mine would readily be appreciated.

Obviously in tile construction I might

place a foraminous member on the side of a building and tile might be placed on said foraminous member. I do not wish to 55 confine the particular construction to roofs, as it is readily adaptable to side walls and to a variety of other uses in building construction.

The invention has for further objects the provision of an improved means for use in building construction which is economical, easy to assemble, which provides maximum rigidity, strength and stress-resistance properties, and which will be adaptable for many 60 uses and purposes, as will more fully appear.

With the above and other objects in view, the invention consists in the novel and useful provision, construction, formation, interrelation of parts, members and features, all 65 as shown in the accompanying drawings, described in the following detailed description, and finally pointed out in claims.

In the drawings:

Figure 1 is a fragmentary perspective view of a foraminous member which may be used in cooperation with tile in building construction;

Figure 2 is a fragmentary cross sectional view on the line 2—2 of Figure 1, and looking in the direction of the appended arrows;

Figure 3 is a fragmentary perspective view of side wall construction, which side wall construction uses a foraminous member with flat slabs in over-lapping relation 85 attached thereto;

Figure 4 is a fragmentary perspective view of a foraminous member having Spanish tile attached thereto, and showing the manner in which the Spanish tile is 90 placed thereon;

Figure 5 is a fragmentary cross sectional view of the construction shown in Figure 4, and showing means of attaching the tile to the foraminous member;

Figure 6 is a fragmentary cross sectional view of a particular form of frame-work construction, which is fire-proof, used in conjunction with Spanish tile;

Figure 7 is a fragmentary detail of the 100 construction shown in Figure 6, and showing the method of applying the Spanish tile to the frame-work;

Figure 8 is a fragmentary cross sectional

view of a method of placing flat slabs of tile on channel irons in roof construction, and the method of attaching the same;

Figure 9 is a modification of the showing in Figure 8 and using L-shaped channel irons in place of the U-shaped shown in Figure 8;

Figure 10 is a fragmentary detail view, certain parts being in section, of flat slabs applied to a foraminous member, which may be used in wall or roof construction;

Figure 11 is a fragmentary cross sectional view taken on the line 11—11 of Figure 10;

Figure 12 illustrates a corrugated metallic roof or wall and the method of forming the same;

Figure 13 is a fragmentary cross sectional view of the construction shown in Figure 12;

Figure 14 shows a loosely woven construction of frame-work which may be utilized in conjunction with tile;

Figure 15 is a fragmentary cross sectional view showing the method whereby a slab, the cross work or foraminous member, as well as a rafter may be tied or united by means of a single bolt or stud;

Corresponding parts in all the figures are designated by the same reference characters.

Referring with particularity to the drawings, I have shown a variety of means for effecting the main object desired, viz: a fire-proof roof or wall construction. In using the word "wall" I wish to be understood as including within its meaning floor-
ing and ceilings.

Referring particularly to Figure 1, I have therein illustrated a construction utilizing what is known as Mission tile A, which Mission tile is placed upon and secured to a frame-work B, said frame-work B in turn being supported upon rafters C. The construction shown in Figure 1 may be utilized for roofing or for side walls, but considering the particular construction in its use for roofs, the rafters C are preferably channel or angle irons, and the frame-work B is likewise preferably formed of metallic members. It will thus be seen that this particular construction differs from the ordinary construction of roofs, in that no wood is used, and that the danger through fire and a collapsing roof is entirely overcome. The particular construction of the frame-work B includes cross members 1 and 2 spaced from each other, and tied together by suitable means, as 2^a. The metallic members 1 and 2 may have a flat face construction, as shown. There is likewise included in the frame-work B further members 3 which are arranged at an angle to the plane of the members 1 and 2, the members 1 and 2 lying in parallel planes, while the members 3 lie in a plane perpendicular or at right angles to the planes of the members 1 and 2. The members 3 may be inter-con-

nected or they may be in a spaced parallel relation to each other, as shown in Figure 1. The members 3 present a corrugated appearance having what may be termed a hill and valley formation, as 4 and 5, respectively. 70 The valley portion may be flattened, as shown at 6 for attachment with the members 1 and 2 through the medium of the connecting means 2^a. In the method of laying the tile A, certain of the tile, as a, lie 75 across between the members 3, while other of said tile A, as b, are supported in position and straddle the members 3. It will be noted that the tile b overlaps the tile a. The tile b is attached to the peak of the 80 hill portion of the members 3 by suitable means 7. The members 3 help sustain the weight of the tile b. It will thus be seen that in the particular construction shown in Figures 1 and 2 that we have a frame-work of diagonal cross members in spaced relation with each of said independent cross members lying in parallel courses with a further series of members joined with said first named members in parallel courses and 85 at angles to said first named members. The tile members are laid in courses, certain of which are carried by and lie upon the first named cross members and between the up-standing members attached to said first 90 named members, while other tile members are carried by the upstanding members and overlap certain of the tile members. This particular construction is of great strength 95 and rigidity. In ordinary building construction where wood is used, it is necessary to brace very thoroughly, due to the great weight of the tile members, and it is obvious that the construction shown in Figures 1 and 2 overcomes the complicated wooden 100 girder construction.

In Figure 3, which illustrates a wall construction, we have a beam D formed of channel iron and to said beam is united or otherwise attached a foraminous member E formed of inter-connected parallel round bars 8 and 9. To said bars may be attached slab members F, as by means 10 passing through said slab members at an upper end thereof and joined with certain of the members 8 and 9. The slab members in Figure 3 resemble shingles and may be used in place of the ordinary shingle construction in buildings. It will at once be seen that this particular construction does away 110 with concrete walls and that a fire-proof building may be easily erected by use of such a construction. It is very easy to imagine building a house by utilizing a construction such as shown in Figure 3. It would only be necessary to cut out certain portions of the member E for the doors and windows, and the time of erecting a house or building could be practically halved. Furthermore, the particular construction is 115 120 125 130

economical requiring no particular skill in the forming of joints, etc., as is now necessary in the ordinary wooden construction of a dwelling. Concrete requires molds and extra workmen. This construction does not require a large number of workmen, nor is it necessary that the workmen be particularly skilled in the erection of the building. The inventor of course realizes that tile must be carefully laid, but if the holes are bored properly in the tile and the foraminous members are delivered cut to size, and properly perforated, it would be a simple matter to assemble to form the sides 15 of a house and the roof.

In Figures 4 and 5 I have illustrated a roof which utilizes Spanish tile G, and said tile is applied to the foraminous member E which was described for Figure 3. It will 20 be noted on reference to Figure 5 that the tile is easily fastened to the foraminous member E by means of twisted wire members 11 passing through perforations in the tile with the wire joined with the foraminous member. In the laying of the Spanish tile it is to be noted that this particular form of tile differs from the tile shown in Figure 1 in that the tile is so laid as to lap under and be overlapped by adjacent tiles 25 of the same rank. Said tile G may be conveniently maintained in position upon the foraminous member E by the securing means 11, as described. Upon reference to Figure 4 it will be seen that the securing 30 means 11 really surrounds and connects with the members 8 and 9 making up the foraminous member E. In the particular construction of the foraminous member E the members 8 and 9 making up the same may 35 be inter-connected, or not, as desired. However, the members D which are termed beams, are provided with U-shaped or other securing means or staples 12 which effectively unite the members 8 and 9 to the 40 same. If the lattice work formation of the member E is joined together at its intersecting point, as 13, it is of course necessary that the securing means 12 be of staple formation.

In Figures 6 and 7 I have illustrated a construction wherein the roof or wall may be formed in a slightly different manner from that illustrated in the figures just described. This construction comprises a 45 twisted strap H. I preferably provide a plurality of said twisted straps, and it will be noted that said twisted strap includes portions as 14 and 15 at right angles to each other in alternate line formation. Said 50 twisted straps H are supported upon suitable rafters formed of channel irons 16. The Spanish roofing tile is here again illustrated, and it will be seen that said tile is formed of oppositely curved portions and 55 that the tile lies in overlapping and under-

lapping relation. The underlap as 17, rests upon the portions as 14 of the strap H in each case, and a tie member, as 18, passes through suitable perforations in the tile and in the portion 14 of the strap, so that the 60 tile is securely held to the strap. This construction of course provides for lattice work, but the space between the lattice work is greater in one direction than in the other. In other words, the strap members H lie in 65 parallel courses short distances apart, while the rafters or beams 16 lie at relatively increased distances apart when considered in proportion to the distance between the strap members H. It is of course obvious that 70 the distance between the rafters 16 would depend upon the strength of the straps and the weight of the tile. In Figure 8 I have shown flat slabs in overlapping relation joined by means of a bolt 19 to channel 75 irons 20, the channel irons in turn being supported upon rafters 21. The combination of the members 20 and 21 provides a construction performing a function identical with the function performed by the 80 construction shown in Figures 3, 4, 6 and 7. The construction shown in Figure 9 is practically identical with the construction shown in Figure 8, with the exception that L-shaped channel irons are used in place of 85 U-shaped. In addition, the tie members may be twisted wires or staples 22 in place of bolts.

In Figures 10 and 11 I have again illustrated the foraminous frame-work E and have placed thereon flat slabs of tile. This tile may be the same as that shown in Figure 3 and designated by F. However, in this particular construction the tile F is 90 united and held to the frame-work E by 100 means of wire staples 23. In Figures 12 and 13 a corrugated form of roofing or wall construction is shown wherein I provide the frame-work which comprises longitudinal and lateral members, with a corrugated 105 metallic covering J. The corrugated covering may be conveniently held to the frame-work by means of bolts as illustrated in Figure 13. In Figure 14 the frame-work is formed of loosely woven members so 110 formed and bent that the bights unite with the bights of other members to form a continuous structure. This form of construction may be utilized in place of the construction shown in Figures 1, 3, and 6, and 115 would serve the purpose in an equally useful manner. If the interlocking portions or bights of said members were not connected, it would of course be necessary to 120 securely join said members to the rafters, providing this construction is used for roofing frame-work. In Figure 15 I have shown a frame-work such as illustrated in Figure 1 in which the cross members 1 and 125 2, as well as the rafter C and any one of 130

the slabs may all be united at a given point by means of a bolt or stud such as shown at 2^a in Figure 1.

From all the figures it will be seen that 5 I have provided a new and novel construction which is particularly useful for buildings that use tile, slate or asbestos shingles or slabs of any form, shape or material. Defective electric wiring, spontaneous com- 10 bustion, broken gas mains, are often responsible for roof fires where wooden rafters and sheathing are used. This danger, however, is entirely eliminated by my construction as wooden members are dispensed 15 with.

It is obvious that many changes and variations may be made in practicing the invention, such as my making the construction air-tight by separating all contacts be- 20 tween tiles or other fire-proof material with strips of fireproofed felt, as asbestos felt, or by lining the interior of the roof with fireproofed paper roofing, in departure from the particular description and showing of 25 the drawings, without departing from the true spirit of the invention.

Having thus disclosed my invention, I claim and desire to secure by Letters Patent:

1. In building construction, a frame-work comprising spaced members, and a fireproof covering applied over said members and attached thereto at spaced points; said spaced members intersecting each other in lattice formation; there being 35 arched members applied to said first named members, and said fireproof covering comprising members of arched construction applied over said arched members.

2. In building construction, a frame-work comprising spaced members, and a fireproof covering applied over said members and attached thereto at spaced points; said spaced members intersecting each other in lattice formation; there being arched members applied to said first named members, and said fireproof covering comprising members of arched construction applied over said arched members; said fireproof covering comprising tile provided with perforations through which tie devices are extended to joint such tile with such arched members.

3. In building construction, a foraminous lattice-like frame-work provided with arched members, and a plurality of fireproof tile applied to said arched members and in overlapping relation. 55

4. In building construction, a lattice-like frame-work provided with arched members, and a plurality of fireproof tile applied to 60 said arched members and in overlapping relation; said tile having perforations through which tie devices may be extended to secure the tile to the frame-work.

5. In building construction, a lattice-like frame-work provided with arched members, and arched fireproof members applied over 65 said arched members.

6. In building construction, a lattice-like frame-work provided with arched members, 70 and arched fireproof members applied over said arched members; there being other fire-proof members applied to said frame-work between said arched members.

7. In building construction, a lattice-like frame-work provided with arched members, and arched fireproof members applied over 75 said arched members; there being other fire-proof members applied to said frame-work between said arched members; said fire-proof members being arranged in overlapping 80 relation.

8. In building construction, a frame-work provided with arched members, and arched fireproof members applied over 85 said arched members; there being other fireproof members applied to said frame-work between said arched members; said fireproof members being applied in overlapping relation; said arched members being arranged in 90 spaced parallel relation.

9. In building construction, a foraminous frame-work provided with arched members, tile applied over such arched members, and 95 means for anchoring the tile.

In testimony whereof, I have signed my name to this specification in the presence of two subscribing witnesses.

AURÈLE VERMEULEN.

Witnesses:

EDNA TURNER,
J. SHUTT.
